UNITED STATES PATENT OFFICE.

JAMES H. BENEDICT, OF DETROIT, MICHIGAN.

SPIKE.

1,206,087.

Specification of Letters Patent. Patented Nov. 28, 1916.

Application filed May 22, 1916. Serial No. 99,047.

To all whom it may concern:

Be it known that I, JAMES H. BENEDICT, a citizen of the United States of America, residing at Detroit, in the county of Wayne 5 and State of Michigan, have invented certain new and useful Improvements in Spikes, of which the following is a specification, reference being had therein to the accompanying drawings.

This invention relates to spikes, and the primary object of my invention is to provide a railway spike that can be easily and quickly driven into a tie, sleeper, or rail supports for preventing lateral and vertical displacement of the rails of a track relative to the roadbed thereof. Easy driving of the spikes is assured by the shape and cross sectional area of the shank of the spike, also by the non-resisting beveled cutting 10 end of the spike. Lateral and vertical displacement of a rail relative to a tie is prevented by the overhanging head of the spike having a retaining rib engaging the base flange of the rail to prevent the rail from creeping from under the head of the spike, such creeping often occurring due to the vibration of the rail set up by heavy rolling stock passing over the same.

Another object of my invention is to furnish a railway spike with a channel shank possessing the same rigidity and strength, for driving and holding purposes, as the ordinary spike. A channel shaped spike shank obtains a firm purchase in a wooden tie without unnecessarily dismembering the fibrous homogeneous mass of the tie, consequently the longevity of a wooden tie is materially increased. To further enhance the wearing qualities of a wooden tie and 20 contribute to its preservation, the shank of the spike contiguous to the head thereof is provided with a liquid shedding member which prevents rain, snow and other matter from entering the tie at the walls of the spike, consequently deterioration of a tie is reduced to a minimum and under ordinary conditions it is practically impossible for the spike to become loose in the tie and tend to release the rail flange held thereby.

50 A further object of my invention is to provide a spike, which besides meeting the various requirements or contingencies of use, possesses merit from a manufacturing standpoint, inasmuch, that it can be made by a spike machine having rolls and dies designed for the formation of the important

parts of the spike. In the first place, a channel bar can be more readily handled in a spike making machine, driving ends easily produced by rolls, and heads readily 60 upset for desired conformation; the ultimate product of the machine being a good spike, as will be better understood from the following detail description.

Reference will first be had to the drawing, wherein—

Figure 1 is a cross sectional view of a portion of the tie supporting a rail, showing a spike in longitudinal section and a spike in elevation; Fig. 2 is a perspective 70 view of a spike in accordance with this invention; and Fig. 3 is a cross sectional view of the same looking toward the head of the spike.

The shank of the spike has a back wall 75 1 and parallel side walls 2, said walls forming a channel throughout the length of the shank. The walls 1 and 2 have the ends thereof shaped to provide a driving end for the spike and considering the lower ends 80 of these walls, the walls 2 are of less length than the wall 1 and have the ends thereof beveled inwardly, as at 3, whereby as the spike is driven into a wooden tie or sleeper, the fibers thereof are separated and forced 85 inwardly into the channel of the spike. The end of the wall 1 is brought to a driving point 4 and the outer side of the wall formed with beveled faces 5, thereby providing a driving point which is essentially 90 triangular in cross section, said point facilitating the starting of the spike in the tie, until the walls of the spike obtain a purchase in the tie for further driving. The point of the spike does not necessarily cut 95 fibers of a wooden tie, but presses the same to one side whereby the same fibers may frictionally hold the walls of the spike and expand and contract without deterioration setting in which has a tendency to loosen 100 an ordinary spike.

The opposite end of the shank is upset and formed to provide an overhanging head 6, said head being oval in plan with a convex liquid shedding top. The head projects from 105 the wall 1 of the shank and has a filler 7 corresponding in width to the shank, thus coöoperating with the head 6 in forming shoulders 8 under which a claw, crowbar or other spike extracting device may be placed 110 for withdrawing the spike from a tie. In forming the filler 7 a transverse rib or re-

taining member is provided to engage in a groove or seat 10 provided therefor in the base flanges 11 of a rail 12. The rib or retaining member 9 depends from the filler or 5 under side of the spike head contiguous to the inner end thereof, whereby it can readily engage in the groove or seat 10, adjacent the outer edge of the base flange 11 when the spike head overhangs the base flange, as best 10 shown in Fig. 1. The groove or seat 10 may be formed when rolling or otherwise producing the rail 12 and in some instances the groove or seat 10 may be only formed in the inner base flanges of rails of a track, whereby 15 the inner spikes of the track engaging the inner base flanges will prevent the rails of the track from spreading due to the great weight of rolling stock that passes over the same. With the retaining members 9 positively 20 engaging in the base flanges 11 of a track, it is practically impossible for the rails of the track to creep from under the heads of the spikes and while this lateral displacement is prevented, it is equally impossible 25 for the rails to become vertically displaced as the inner and outer spikes co-operate in firmly positioning the rails on a tie. With the gage of a track maintained 30 under ordinary conditions, accidents incident to rail displacement are eliminated and the expense of track maintenance reduced to a minimum. Another characteristic feature 35 of the spike is a filler 13 in the channel of the spike and a liquid shedding member 14 adjacent the head of the spike. The filler 13 braces the walls 1 and 2 at their juncture with the head 6, and said filler presents a beveled face whereby the spike can be properly driven into a tie to seat the head thereof on the base flange 11 and the liquid shedding member 14 on the top of a tie. In some 40 instances the filler 13 may be of greater depth than shown, particularly in connection with a heavy spike adapted for driving 45 into an indurate material.

The liquid shedding member 14 is in the form of a web or flange extending outwardly from the walls 2 and the outer side

of the head 6, as best shown in Fig. 2. With this member overlying the top of the tie, 50 water, oil and other liquids are deflected away from the juncture of the spike with the tie, consequently liquid cannot ooze between the spike walls and the tie to cause deterioration around the spike. The member 14 is easily formed during the upsetting and shaping of the headed end of the spike and by terminating at the wall 1 of the spike it does not interfere with proper positioning 55 of the spike head relative to the rail flange. 60

One embodiment of my invention has been illustrated, but it is to be understood that the spike is susceptible of such variations and modifications as fall within the scope of the appended claims. 65

What I claim is:—

1. A spike comprising a channel shaped shank, having walls of equal thickness beveled at one end of the spike with the beveled edge of two of the walls terminating at the 70 beveled edge of the other wall to provide a pointed shank end, a head at the opposite end of said shank, and a liquid shedding member carried by the side and outer faces of said shank contiguous to said head. 75

2. A spike comprising a channel shaped shank having opposed walls at one end thereof beveled and the connecting wall of said opposed walls beveled inwardly to provide a flat pointed end extending below the 80 beveled ends of the opposed walls of said spike, a head at the opposite end of said shank, a filler under said head between the opposed walls of said spike, a depending retaining member carried by said head adapted for engagement in the base flange 85 of a rail, and a liquid shedding member carried by the three walls of said shank contiguous to said head.

In testimony whereof I affix my signature 90 in presence of two witnesses.

JAMES H. BENEDICT.
